UNITED STATES PATENT OFFICE.

ISAAC PATRICK, OF HASTINGS, MICHIGAN, ASSIGNOR TO CONSOLIDATED PRESS COMPANY, OF HASTINGS, MICHIGAN, A CORPORATION OF MICHIGAN.

TOGGLE DRAWING-PRESS.

1,255,332.

Specification of Letters Patent. Patented Feb. 5, 1918.

Application filed April 6, 1917. Serial No. 160,212.

To all whom it may concern:

Be it known that I, ISAAC PATRICK, a subject of the King of Great Britain, residing at Hastings, in the county of Barry and State of Michigan, have invented certain new and useful Improvements in Toggle Drawing-Presses; and I hereby declare that the following is a full, clear, and exact description thereof, reference being had to the accompanying drawings, which form part of this specification.

This invention relates to presses for drawing and stamping metal, and has particular reference to the means for operating the blank-holder devices in such presses, and to the means for adjusting such devices.

The embodiment of the invention illustrated may be described in brief as a novel toggle-movement for operating the outer or blank-holder-slide of a toggle drawing press, so that such blank-holder-slide will descend and engage the work and commence its dwell before the crank operating the inner drawing slide or plunger has begun to operate on the work, and the blank-holder-slide will continue to dwell and hold the work until the drawing-slide has completed its downward stroke or work, after which the blank-holder-slide will rise preferably substantially in unison with the drawing-slide until the blank-holder-slide has completed its up stroke.

The invention further includes novel means for adjusting the blank-holder-slide as a whole to suit different thicknesses of material of work to be operated upon; and also means for independently adjusting parts of the blank-holder to prevent unequal strains thereon.

I will describe one practical embodiment of the invention, as illustrated in the accompanying drawings, so that the same may be fully understood by those familiar with the art, and will summarize in the claims following such description, the essential features and combinations for which protection is desired; but I do not consider the invention restricted to the specific form or construction of parts illustrated in the drawings.

In said drawings:

Figure 1 is a partial front elevation of a toggle-drawing press with my novel blank-holder-operating mechanism applied thereto.

Fig. 2 is a partial side view of Fig. 1 illus-

trating more particularly the blank-holder- 55 operating mechanism in elevation.

Fig. 3 is a detail top plan view of Fig. 2.

Fig. 4 is an enlarged detail vertical section on the line 4—4 Fig. 2.

Fig. 5 is a detail view showing the plunger or drawing-slide approximately on half stroke, and indicating the blank-holder-slide at the beginning of its dwell or end of down stroke.

Fig. 6 is a transverse section on line 6—6 65 Fig. 5.

Fig. 7 is a detail view of the rack-yokes N, O, and pinion K.

Figs. 8 and 9 are smaller front elevations of the parts for operating the blank-holder- 70 slide and adjusting same, partly in section and detached; the parts being illustrated in different positions in the two figures.

The invention may be applied to various forms of drawing or stamping presses, or 75 "toggle-presses" now in use; and such a press is conventionally shown in part in the drawings; in which A represents the plunger or drawing-slide, of a well known type of drawing press, connected in the usual manner by a pitman A' to a crank B' on a crank shaft B journaled in the main frame 1 of the press; and which shaft may be rotated by gearing in the usual manner, so as to reciprocate the drawing-slide during each 85 rotation of said shaft B.

Coacting with the drawing-slide is a blank-holder-slide, which may be of any suitable construction, adapted to hold the stock or work during the drawing or stamping operation thereon; and said blank-holder-slide must, therefore, dwell or remain stationary during such operation.

In accordance with my invention the blank-holder-slide is operated by toggle-links and connections so arranged that they will first lower the blank-holder-slide onto the work and hold it at rest thereon during the drawing operation, and thereafter lift the blank-holder-slide on the up stroke of 100 the drawing-slide to permit the operator to remove the drawn shell or stamping, or insert a new blank in the die ready to be drawn or stamped.

The blank-holder-slide C is shown as ad- 105 justably connected, as hereinafter described, to bars W, each of which is pivotally connected at its ends (see Fig. 2) to the lower

ends of links V, which are in turn pivotally connected at their upper ends to arms U on rock shafts T, journaled in bearings 2 on the frame 1, two of said shafts being arranged at opposite sides of the main frame.

The rock shafts T, carry arms S, from which are suspended links P, to which are pivotally connected links Q; these links Q are pivotally connected at their lower ends 10 to brackets R, on the main frame of the machine, as indicated in Fig. 1.

To the bolt p that pivotally connects the links P and Q at the left hand side of the machine is also pivotally connected the 15 shank of a yoke member N which embraces a shaft 3 journaled in the main frame and in the end of a bracket 4 attached to said frame. Yoke N carries a rack N' which engages with a pinion K on the shaft 3.

20 To the bolt p' connecting links P, Q at the right hand side of the machine is also pivotally connected the shank of a yoke member O which also embraces pinion K and has a rack O' engaging said pinion at 25 the side opposite the rack N', see Figs. 2 and 7.

On the shaft 3 is also mounted a second gear H which has a reduced hub portion H'. Said pinion H meshes with a rack G on yoke 30 F that embraces the pinion H, and said yoke has a reduced slotted portion J that embraces the hub H' of the pinion H and insures constant mesh of rack G therewith. The yoke F also has a slot F' which slidably 35 engages the preferably reduced end B² of the shaft B, and is retained slidably in engagement therewith by means of a collar X suitably secured to the end B² of shaft B.

A cam D is mounted on the shaft B adjacent the yoke F. Said cam is preferably 40 a race cam and its groove D' is engaged by a roller on a stud E attached to the yoke F, so that yoke F will be raised and lowered by the action of the cam D; and as the rack 45 G on said yoke is in mesh with pinion H, it causes said pinion to rock or turn alternately backward and forward.

The pinion K is made fast to pinion H, in 50 any suitable manner, so that it must rotate therewith; and when pinion H is turned pinion K turns therewith and will through racks N', O' move the yokes N and O oppositely, outward or inward as the case may be; and these yokes operate the opposite 55 toggles formed by links P, Q and will straighten or break such toggles.

The straightening or breaking of the toggles P, Q causes a corresponding rocking movement of the related shafts T, through 60 the connections S; and this causes the toggles formed by arms U and connected links V to raise or lower the bars W, and thus raise or lower the blank-holder-slide.

When crank shaft B is revolved cam D 65 must revolve with it; this cam in turn oper-

ates yoke F which must reciprocate on a straight line (owing to the extensions on pinion H and crank shaft B passing through the slots in said yoke). The yoke F causes pinions H and K to revolve, and impart motion to rack yokes N and O which in turn operate toggles P, Q; which in turn cause cranks S to move in accordance therewith and rock shafts T and through toggles U, V raise or lower the blank-holder-slide, see 75 Figs. 1 and 2.

It is obvious that the cam surface of the cam D can be shaped to impart any desired movement or dwell to the blank-holder-slide during the rotation of said cam; also 80 that when the blank-holder-slide is at the lower end of its stroke, and during the time that the work is being performed, the toggles formed by links P, Q and the toggles formed by arms U, and links V are in 85 straight or unyielding position, and are so held by the rack yokes N and O controlled by pinions H, K and cam D; said toggles firmly resist any upward pressure exerted on the blank-holder-slide and cause it to 90 hold the stock securely and properly during the effective part of the working stroke of the drawing-slide.

Preferably, as in the construction shown, all the wrist pins or pivot bolts in the toggle 95 mechanism are supported in "double shear" or at both ends, thus preventing any tendency of the toggles to "weave" or deflect laterally while under pressure; and insuring a perfect dwell during the drawing 100 stroke.

The outer end of the shaft 3 carrying the pinions being supported by a substantial bracket 4 said shaft can withstand the 105 strains to which it is subjected without deflection.

The racks or rack yokes N and O preferably have a toothless member opposite to the rack sliding upon the pinion K and thereby keeping their rack members N', O' 110 in perfect mesh with said pinion, see Fig. 7; and no matter what position relative to their pivots R' on brackets R the links Q may assume, the rack yokes O, N lie always radially of the shaft 3 carrying the pinion K. 115

The means shown for adjusting the blank-holder-slide are as follows: Two depending threaded rods a, are connected to each bar W in any suitable manner. As shown each rod has a shoulder a' below the bars W, and is fastened thereto by nuts a², a³ screwed on the threaded upper end of the rod above the bar, (see Figs. 1, 2, 8 and 9).

These rods a respectively pass through brackets or lugs C' on the sides of the 125 blank-holder-slide C and are engaged with internally threaded nuts b below the lugs C' which nuts preferably have circular portions entering the lugs C' to steady the nuts relative thereto, (see Fig. 2), and said nuts 130

are provided with worm gears b' by which the nuts may be turned to adjust the rods a .

Screwed on each rod a above the lug C' are adjusting and locking nuts d, d' ; and 5 below the worm b' on each rod a are adjusting and locking nuts e, e' .

In the example shown there are four of these rods a connected with the blank holder C , two at each side thereof; and the rods a 10 at opposite sides of the blank-holder are preferably connected to the same bar W .

Mounted upon the blank-holder-slide C , intermediate each pair of adjacent worm gears b' , is a casting f in which is journaled 15 a shaft g carrying worms g' on its ends; which worms mesh with the worm gears b' on the adjacent rods a . The shaft g and worms g' are arranged at both front and back of the blank-holder-slide.

20 On one end of each worm shaft g is a spiral or helical gear g^2 which meshes with a helical gear h^2 mounted on a shaft h , running through the blank-holder from front to back, or otherwise suitably journaled 25 thereon; said shaft is provided with suitable means for rotating it; a hand wheel h' being shown.

When it is desired to adjust the blank-holder upwardly the nuts d, d' are loosened; 30 if the blank-holder is to be adjusted downwardly nuts e, e' are loosened. The hand wheel h' is then turned so as to cause worms h^2 to turn shafts g and cause worms g' to rotate the worm gears b' in the desired direction to raise, or lower, the blank-holder relatively to the bars W .

As the blank-holder is suspended on the rods a by the worm nuts b , it follows that as these nuts are raised or lowered on the rods, 40 the blank-holder-slide is similarly adjusted to position. After the blank-holder-slide is adjusted all the nuts should be securely tightened.

If after the blank-holder-slide has been 45 adjusted to suit the general requirements, it is necessary to adjust any particular corner of the blank-holder to hold more securely at that point the sheet, or work to be drawn, the nuts a^2, a^3 on the adjacent rod are loosened and a wrench applied to the hexagon portion a' of such rod, and it is turned until the desired adjustment is obtained. Then nuts a^2, a^3 are tightened.

By this construction in addition to means 55 for simultaneously adjusting all the rods a , each rod can be individually adjusted; and this saves much time and inconvenience in adjusting the blank-holder to suit different thicknesses of work or blanks, and also obviates straining the blank-holder by unequal adjustment.

The novel toggle movement described for 60 operating the blank-holder-slide is compact, and powerful. It can be readily located on the upper part of the press in a position

where the operator is in no danger from moving parts; and where it will not prevent or obstruct the free access by the operator to all parts of the press.

With this invention any desired stroke 70 and time of the dwell of the blank-holder-slide can be obtained by properly designing the cam D and the stroke and dwell of the blank-holder can be varied to suit different kinds of work by changing the said cam for 75 one designed to suit such work. And the blank-holder-slide can be readily adjusted to suit the particular kind of blank to be operated upon.

What I claim is:

1. In a press, the combination of a drawing-slide, means for reciprocating the slide; a blank-holder, a rock shaft, links connecting said shaft with the blank holder, a toggle connected with the shaft and with a relatively fixed point, a rocking pinion, a rack bar engaging the said pinion and connected with the toggle to straighten or break same, and means for oscillating said pinion. 80

2. In a press, the combination of a drawing-slide, means for reciprocating the slide, a blank-holder-slide, a rock shaft, a toggle pivotally connected with said shaft and with the blank-holder-slide, a second toggle connected with the shaft and with a relatively 95 fixed point, a rocking pinion, a rack bar engaging the said pinion and connected with the second toggle to straighten or break same, and cam actuated means for oscillating said pinion. 100

3. In a drawing press, the combination of a drawing-slide, means for reciprocating said slide; a blank-holder, rock shafts at opposite sides of the machine, links connecting said shafts with the blank-holder; toggles respectively connected with the said shafts and with relatively fixed points, a rocking pinion, a rack engaging said pinion, and connected with the toggle to straighten or break same, and means for oscillating said pinion. 110

4. In a drawing press the combination of a drawing-slide, means for reciprocating said slide; a blank-holder-slide, rock shafts at opposite sides of the machine, toggles pivotally connecting said shafts with the blank-holder-slide; second toggles respectively connected with the said shafts and with relatively fixed points, a rocking pinion, a rack engaging said pinion, and connected with the second toggle to straighten or break same, and cam actuated means for oscillating said pinion. 115

5. In a drawing press the combination of a drawing-slide, means for reciprocating said slide; a blank-holder-slide, rock shafts at 120 opposite sides of the machine, links pivotally connecting arms on said shafts with the blank-holder-slide, toggles respectively connected with the said shafts and with relatively fixed points, a rocking pinion, rack 125

- bars engaging the opposite sides of said pinion and connected with the pivot joints of the toggles to straighten or break same, and means for rocking said pinion.
5. In combination with a press having a drawing-slide and a blank-holder-slide; of means for operating the blank-holder-slide comprising a pinion, means for oscillating this pinion, a rack engaging said pinion, a 10 rock shaft, an arm connected with the rock shaft, a toggle having one member pivotally connected to the arm of the rock shaft the other member pivotally connected to a relatively fixed support, a connection between the toggle and said rack so that the toggle is straightened or broken by the action of said rack; and connections between said rock shaft and the blank-holder-slide for operating the latter.
- 15 6. In combination with a press having a drawing-slide, and a blank-holder-slide; of means for operating the blank-holder-slide comprising an oscillatory pinion, a rack engaging said pinion, a rock shaft, connections between said rock shaft and the blank-holder-slide for operating the latter; an arm connected with the rock shaft, a toggle having one member pivotally connected to the arm of the rock shaft the other member 20 pivotally connected to a relatively fixed support, a connection between the center pivot of the toggle and said rack so that the toggle is straightened or broken by the action of said rack; and a cam and connections for 25 operating the oscillatory pinion.
7. In combination with a drawing-press having a reciprocating plunger, a main shaft and connections for operating said plunger, and a work-holder-slide; of means for operating said work-holder-slide comprising opposite rock shafts mounted on the frame of the machine, arms on said shafts, links connecting the arms on said shaft with the work-holder-slide, toggles pivotally connected 30 with arms on said shafts, and with relatively fixed pivots, an oscillatory pinion, and racks engaging opposite sides of said pinion and extending in opposite directions and respectively connected with the pivot joints of the 35 toggles to straighten or break same; and means for oscillating said pinion.
8. In combination with a drawing-press having a reciprocating plunger, a main shaft and connections for operating said plunger, and a work-holder-slide; of means for operating said work-holder-slide comprising opposite rock shafts mounted on the frame of the machine, arms on said shafts, links connecting the arms on said shaft with the work-holder-slide, toggles pivotally connected 40 with arms on said shafts, and with relatively fixed pivots, an oscillatory pinion, and racks engaging opposite sides of said pinion and extending in opposite directions and respectively connected with the pivot joints of the 45 toggles to straighten or break same; and means for oscillating said pinion.
9. In combination with a drawing-press having a reciprocating plunger, a main shaft and connections for operating said plunger, and a work-holder-slide; of means for operating said work-holder-slide comprising opposite rock shafts mounted on the frame of the machine, arms on said shafts, links connecting the arms on said shaft with the 50 work-holder-slide, toggles pivotally connected with arms on said shafts, and with relatively fixed pivots, an oscillatory pinion, rack yokes engaging opposite sides of said pinion and extending in opposite directions and respectively connected with the pivot 55 joints of the toggles to straighten or break same; and cam actuated means for oscillating said pinion.
10. In combination with a drawing machine having a reciprocating plunger, and a main shaft and connections for operating said plunger, of a work-holder-slide; opposite rock shafts mounted on the frame of the machine, arms on said shafts, links connecting arms on said shafts with the work-holder-slide, toggles pivotally connected with arms on said shafts and with relatively fixed pivots; an oscillatory pinion; rack yokes engaging opposite sides of said pinion and extending in opposite directions and respectively connected with the toggles to straighten or break same, a rack for oscillating said pinion, and means for reciprocating said latter rack, substantially as described. 70 75 80 85
11. In a drawing press, the combination of a drawing-slide, a main shaft and connections for reciprocating said drawing-slide; of a work-holder-slide; a pair of parallel shafts mounted on the machine, arms connected with said shafts, links connecting said arms with the work-holder-slide; other arms connected with said shaft, a pair of toggle links respectively connected with the latter arms on the shafts and with fixed points on the frame, an oscillatory pinion intermediate the said toggles, oppositely disposed racks respectively connected with the toggles and engaging opposite sides of said oscillatory pinion, a slidable rack for oscillating said pinion, and a cam and means operated by said cam for reciprocating said slidable rack. 90 95 100 105
12. In a drawing press, the combination of a reciprocating drawing-slide, a main shaft and connections for reciprocating said drawing-slide, and a work-holder-slide; of means for operating the work-holder-slide comprising a pair of parallel shafts mounted on the machine above the work-holder-slide, arms connected with said shafts, links connecting said arms with the work-holder-slide; other arms connected with said shaft, a pair of toggles respectively connected with the latter arms on the shafts and with fixed points on the frame; an oscillatory pinion intermediate the said toggles, oppositely disposed rack-yokes respectively connected with the knee pivots of the toggles and engaging opposite sides of said oscillatory pinion, a slidable rack for oscillating said pinion, a rotatable race cam, and means connected with said slidable rack and engaging said race cam for reciprocating said rack. 110 115 120 125 130
13. In combination with a press having a reciprocating drawing-slide, and means for operating said slide; a blank-holder slide, a rock shaft, a toggle connecting the rock shaft with the blank-holder-slide, a second toggle pivotally connected with an arm on

said shaft and with a relatively fixed point, and cam actuated means directly connected with the pivot joint of the latter toggle for straightening or breaking such toggle.

5 14. In combination with a press having a reciprocatory drawing-slide, and means for operating said slide; a blank-holder-slide, a rock shaft, a toggle connecting the rock shaft with the blank-holder-slide, a second toggle 10 pivotally connected with the shaft and with a relatively fixed point, a member pivotally connected with the pivot joint of the second toggle, and a cam actuated means for operating said member to cause it to straighten 15 or break the toggle.

15. In combination with a drawing press having a reciprocatory drawing-slide, and means for operating said drawing-slide; of a work-holder-slide adapted to hold the work while the drawing-slide is operating thereon, a pair of rock shafts, toggle-links connecting the rock shafts with the blank-holder, arms on said shafts, toggles pivotally

connected with the arms on said shafts and with relatively fixed points, members directly connected with the pivot joints of the latter toggles, and means for operating said members to straighten or break such toggles, substantially as described. 25

16. In a drawing press, a reciprocatory drawing-slide, means for operating said drawing-slide; a work holder adapted to hold the work while the drawing-slide is operating thereon, a pair of rock shafts provided with arms, links connecting arms on 35 the rock shafts with the blank-holder-slide, toggles respectively pivotally connected with other arms on said shafts and with relatively fixed points, members directly connected with the pivot joints of the toggles and 40 means for actuating said members to straighten or break the toggles, substantially as described.

In testimony that I claim the foregoing as my own, I affix my signature.

ISAAC PATRICK.
